MCRAE & KEELER, OF ATTLEBORO, MASSACHUSETTS, A FIRM.

FASTENER.

SPECIFICATION forming part of Letters Patent No. 769,208, dated September 6, 1904.

Application filed December 29, 1903. Serial No. 186,999. (No model.)

To all whom it may concern:

Be it known that I, WILLIAM E. COLES, a citizen of the United States, residing at Attleboro, in the county of Bristol and State of Massachusetts, have invented a new and useful Improvement in Fasteners, of which the following is a specification.

This invention has reference to an improvement in fasteners, and more particularly to an improvement in that form of fasteners used to fasten or secure articles to wearing-apparel or to fasten articles of wearing-apparel together. In fasteners or clasps of this nature as heretofore constructed two operations are required—an operation of the mechanism to secure the fastener and an operation of the mechanism to release the fastener from the outside of the wearing-apparel to which it was attached.

20 The object of my invention is to improve the construction of a fastener, whereby the fastener is secured to an article of wearing-apparel automatically and released by pressure on a lever in the fastener.

25 My invention consists in the peculiar and novel construction of a fastener having a U-shaped frame stamped from sheet metal having a spring tension, a spring-tongue, bearings, and an eye formed integral with the frame, a fastening-lever having pivots working in the bearings and held in its closed position by the spring-tongue, and a cap adapted to cover the front of the fastener and hold the fastening-lever in its operative position 35 in the frame, as will be more fully set forth hereinafter.

Figure 1 is a plan view of the blank forming the U-shaped frame of the fastener, showing the spring-tongue, bearings, and the eye formed integral with the frame. Fig. 2 is a plan view of the blank forming the fastening-lever, showing the pivots, corrugated end, and thumb-piece on the lever. Fig. 3 is a plan view of the blank forming the cap, showing the aperture through which the fastening-lever extends. Fig. 4 is a front view of the completed fastener constructed from the blanks shown in Figs. 1, 2, and 3; and Fig. 5 is a sectional view taken on line XX of Fig.

4, showing the fastening-lever closed in full 50 lines and in the open position in broken lines.

In the drawings, *a* indicates the U-shaped frame, *b* the fastening-lever, and *c* the cap of my improved fastener. The frame *a* is stamped from sheet metal having a spring 55 tension and bent substantially U shape to form the back *a'* and the front *a''*. The spring-tongue *a''*, which bears on the fastening-lever, the stamped-up bearings *a⁴* *a⁴* for the pivots of the fastening-lever, and the eye *a⁵* for attaching articles to the fastener are all formed in the front *a''* integral with the frame. The fastening-lever *b* has the pivots *b'* *b''*, the inner corrugated end *b²*, and the outer end formed into the thumb-piece *b³*. The cap *c* 65 has the aperture *c'* for the fastening-lever and is secured to the front *a''* of the fastener by rolling the edges *c²* *c²* over and under the edges of the frame. The cap *c* has preferably an ornamental design, as shown in Figs. 3 and 4. 70

When the parts of the fastener are assembled, the fastening-lever *b* extends through the opening *a⁶* on the front *a''* of the frame between the bearings *a⁴* *a⁴*. The pivots *b'* *b''* of the fastening-lever *b* are held in the bearings *a⁴* *a⁴* in the frame by the face of the cap *c*. The spring-tongue *a''* exerts a spring tension 75 on the fastening-lever *b* to hold the end *b²* against the back *a'* of the fastener. The thumb-piece *b³* on the fastening-lever extends 80 outward on the front of the fastener through the aperture *c'* in the cap, as shown in Figs. 4 and 5.

In the operation of my improved fastener the fastener is secured automatically by forcing the fabric between the front and back of the fastener. This brings the fabric against the fastening-lever *b*, forcing the end *b²* of the lever forward against the tension of the spring-tongue *a''*. The end *b²* of the lever is 85 now forced into the fabric by the tension of the spring-tongue, securely holding the fastener to the fabric. The fastener may be instantly released from the fabric by pressure on the thumb-piece *b³* of the fastening-lever 90 to move the end *b²* of the lever forward, as shown in broken lines in Fig. 5.

The fastener when once secured is practi-

cally locked to the fabric and cannot be released except by pressure on the thumb-piece of the fastening-lever. An upward movement of the fastener by accident or other means tends to force the inner end of the fastening-lever more firmly into the fabric.

By my improved construction of a fastener the fastener is automatically secured to the fabric and is instantly released from the fabric when required.

Having thus described my invention, I claim as new and desire to secure by Letters Patent—

In a fastener, a U-shaped frame, a spring-tongue, bearings, and an eye all formed integral with the frame, a fastening-lever hav-

ing a thumb-piece, pivots, and a corrugated end, and a cap having an aperture for the fastening-lever secured to the frame by rolling the edges of the cap over and under the edges of the frame, the whole adapted to pivotally secure the fastening-lever in the frame under spring tension and at an angle from the open end of the frame, as described.

In testimony whereof I have signed my name to this specification in the presence of two subscribing witnesses.

WILLIAM E. COLES.
